U.S. Appl. No. 29/532,216, filed Jul. 2, 2015; title: Warming Sleeve;
Inventor(s): Zmrhal et al.

Primary Examiner — Terry Wallace

(74) *Attorney, Agent, or Firm* — Thompson Coburn LLP;
Matthew Himich

(57) **CLAIM**

The ornamental design for a warming sleeve, as shown and described.

DESCRIPTION

FIG. 1 is a front, right side perspective of the warming sleeve showing our new design, with the upper portion secured to the lower portion, and shown as used with an exemplary pan;

FIG. 2 is an exploded front, right side perspective of the warming sleeve showing the upper portion and the lower portion thereof;

FIG. 3 is a top view of the lower portion of the warming sleeve;

FIG. 4 is a bottom view of the lower portion of the warming sleeve;

FIG. 5 is a right side elevational view of the lower portion of the warming sleeve;

FIG. 6 is a left side elevational view of the lower portion of the warming sleeve;

FIG. 7 is a front side elevational view of the lower portion of the warming sleeve;

FIG. 8 is a back side elevational view of the lower portion of the warming sleeve;

FIG. 9 is a bottom plan view of the upper portion of the warming sleeve;

FIG. 10 is a top plan view of the upper portion of the warming sleeve;

FIG. 11 is a first side elevational view of the upper portion of the warming sleeve, the opposite side being identical thereto; and,

FIG. 12 is an end elevational view of the upper portion of the warming sleeve, the opposite end view being identical thereto.

The broken lines are for the purpose of illustrating environment, and form no part of the claimed design.

1 Claim, 11 Drawing Sheets
